(57) **CLAIM**

The ornamental design for a handle for a safety razor, as shown and described.

DESCRIPTION

FIG. 1 is a top perspective view of a handle for a safety razor connected to a cartridge head showing our new design; FIG. 2 is a bottom perspective view thereof; FIG. 3 is a top perspective view of the handle without the cartridge head;

FIG. 4 is a top plan view thereof; FIG. 5 is a bottom plan view thereof; FIG. 6 is a left side elevational view thereof; FIG. 7 is a right side elevational view thereof; FIG. 8 is a front elevational view thereof; and, FIG. 9 is a rear elevational view thereof.

The cartridge head shown in broken lines illustrates the environment of the handle for a safety razor and forms no part of the claimed design.
